US00D638011S

(12) **United States Design Patent**
Kuo et al.

(10) **Patent No.:** **US D638,011 S**
(45) **Date of Patent:** **** May 17, 2011**

(54) **PORTABLE COMPUTER**

(75) Inventors: **Hui-Chi Kuo**, Taipei (TW); **Lian-Tien Ke**, Taipei (TW); **Chung-Jen Chung**, Taipei (TW); **You-Ren Chen**, Taipei (TW); **Ching-Hui Yeh**, Taipei (TW); **Po-Wen Huang**, Taipei (TW)

(73) Assignee: **ASUSTeK Computer Inc.**, Taipei (TW)

(**) Term: **14 Years**

(21) Appl. No.: **29/378,372**

(22) Filed: **Nov. 3, 2010**

(51) **LOC (9) Cl.** **14-02**

(52) **U.S. Cl.** **D14/315**

(58) **Field of Classification Search** ..... D14/315-328, D14/345; D18/1, 2, 7, 11; 235/145 A, 145 R; 341/22, 23; 345/104, 156, 168, 169, 173, 345/87, 901-905; 361/679.02, 679.09, 679.26, 361/679.27; 400/486, 489

See application file for complete search history.

(57) **CLAIM**

The ornamental design for a portable computer, as shown and described.

DESCRIPTION

FIG. 1 is a perspective view of a portable computer showing our design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top elevational view thereof;

FIG. 7 is a bottom elevational view thereof;

FIG. 8 is a partially enlarged section thereof “8” in FIG. 4; and,

FIG. 9 is a partially enlarged section thereof “9” in FIG. 6.

1 Claim, 7 Drawing Sheets

FIG. 1

FIG. 2

FIG. 3

FIG. 4

FIG. 5

FIG. 6

FIG. 7

FIG. 8

FIG. 9
